DESIGN FOR AN INFANT'S BIB

Ella Contrisciani, New York, N. Y.

Application January 18, 1945, Serial No. 117,494

Term of patent 7 years

(Cl. D3—26)

To all whom it may concern:

Be it known that I, Ella Contrisciani, a citizen of the United States of America and resident of New York, county of New York, State of New York, have invented a new, original, and ornamental Design for Infant's Bib, of which the following is a specification, reference being had to the accompanying drawing, forming a part thereof, in which

Fig. 1 is a face view of an infant's bib embodying my design, and

Fig. 2 is an edge view thereof.

The back of the bib is plain and unornamented.

The characteristic feature of my design resides in the combination on the bib disclosed of the specific applique thereon as shown.

I claim:

The ornamental design for an infant's bib, as shown and described.

ELLA CONTRISCIANI.
